US00D756777S

(12) **United States Design Patent**
Berge et al.

(10) **Patent No.:** US D756,777 S
(45) **Date of Patent:** ** *May 24, 2016

(54) **CLOSURE**

(71) Applicant: **Silgan White Cap LLC**, Downers Grove, IL (US)

DE 296 09 596 U1 10/1996
JP 10-181758 A 7/1998

(Continued)

(72) Inventors: **Gary Berge**, Crystal Lake, IL (US); **Darren Neputy**, Palos Hills, IL (US)

OTHER PUBLICATIONS

(73) Assignee: **Silgan White Cap LLC**, Downers Grove, IL (US)

U.S. Appl. No. 29/449,192, filed Mar. 14, 2013, Neputy et al.

(*) Notice: This patent is subject to a terminal disclaimer.

(Continued)

(**) Term: **14 Years**

(21) Appl. No.: **29/482,293**

(22) Filed: **Feb. 17, 2014**

Primary Examiner — Robert M Spear

(51) LOC (10) Cl. 09-07

(74) Attorney, Agent, or Firm — Reinhart Boerner Van Deuren s.c.

(52) U.S. Cl.

FIG. 1 is a top perspective view of the claimed design; FIG. 2 is a top view of the claimed design of FIG. 1; FIG. 3 is a bottom view of the claimed design of FIG. 1; FIG. 4 is a front view of the claimed design of FIG. 1, the rear view being the same as the front view; FIG. 5 is a right side view of the claimed design of FIG. 1, the left side view being the same as the right side view; FIG. 6 is a bottom perspective view of the claimed design of FIG. 1; FIG. 7 is a second top perspective view of the claimed design of FIG. 1; and, FIG. 8 is a second bottom perspective view of the claimed design of FIG. 1.

The broken lines in the drawings represent unclaimed environmental subject matter and form no part of the claimed design.

The dash/dot/dot/dash lines in the drawings represent boundaries of the claim.

1 Claim, 8 Drawing Sheets
